(57) **CLAIM**

The ornamental design for a telephone handset, as shown and described.

DESCRIPTION

FIG. 1 is a front view of the handset with the cover closed, according to one embodiment of our new ornamental design. FIG. 2 is a front view of the handset with the cover closed, according to an alternative embodiment of our new ornamental design, having a transparent window in the cover, and with such structure as may be visible through the window not forming part of the claimed design.

FIG. 3 is a left side elevation of the handset, with the cover closed, applicable to both embodiments.

FIG. 4 is a right side elevation of the handset, with the cover closed, applicable to both embodiments.

FIG. 5 is a top elevation of the handset of the embodiment of FIG. 1, with the cover closed.

FIG. 6 is a bottom elevation of the handset with the cover closed, applicable to both embodiments.

FIG. 7 is a rear elevation of the handset with the cover closed, applicable to both embodiments.

FIG. 8 is a right side elevation of the handset, with the cover open, applicable to both embodiments.

FIG. 9 is a front elevation of the handset, with the cover open, applicable to both embodiments.

FIG. 10 is a right side elevation of the handset, with the cover open, applicable to both embodiments.

FIG. 11 is a rear elevation of the handset with the cover open according to the embodiment of FIG. 1; and,

FIG. 12 is a rear elevation of the handset with the cover open according to the embodiment of FIG. 2.
